DESIGN FOR A NOVELTY PUZZLE

Henry Herbert Wightman, Vancouver, British Columbia, Canada

Application February 18, 1939, Serial No. 83,070

Term of patent 3½ years

To all whom it may concern:

Be it known that I, Henry Herbert Wightman, a subject of the King of Great Britain, residing at 1171 West 32nd Avenue, Vancouver, British Columbia, Canada, have invented a new, original, and ornamental Design for Novelty Puzzles, of which the following is a specification, reference being had to the accompanying drawing, forming part thereof.

I claim:

The ornamental design for a novelty puzzle, substantially as shown.

HENRY HERBERT WIGHTMAN.
